(21) Appl. No.: **29/737,721**

The ornamental design for a laser beam-combining engine with laser resonators, substantially as shown and described.

(22) Filed: **Jun. 11, 2020**

DESCRIPTION

(51) LOC (13) Cl. **15-09**

FIG. 1 is a perspective view of a laser beam-combining engine with laser resonators depicting the new design;

(52) U.S. Cl.

FIG. 2 is a left-side elevation view of the laser beam-combining engine with laser resonators of FIG. 1;

USPC **D15/127**

FIG. 3 is a back view of the laser beam-combining engine with laser resonators of FIG. 1;

(58) **Field of Classification Search**

FIG. 4 is a right-side elevation view of the laser beam-combining engine with laser resonators of FIG. 1;

USPC D15/5, 122, 127, 199, 1, 4

FIG. 5 is a front view of the laser beam-combining engine with laser resonators of FIG. 1;

CPC H01S 3/036; H01S 3/073; H01S 5/02218;

FIG. 6 is a top view of the laser beam-combining engine with laser resonators of FIG. 1;

H01S 5/02315; H01S 5/0233

FIG. 7 is a bottom view of the laser beam-combining engine with laser resonators of FIG. 1; and,

See application file for complete search history.

FIG. 8 is another perspective view of the laser beam-combining engine with laser resonators of FIG. 1.

(56) **References Cited**

The broken lines showing features of the laser beam-combining engine with laser resonators form no part of the claimed design.
